UNITED STATES PATENT OFFICE.

GEORGE HOWARD, OF BERNERS STREET, OXFORD STREET, COUNTY OF MIDDLESEX, ENGLAND.

CONSTRUCTION OF FLOORS AND CEILINGS.

SPECIFICATION forming part of Letters Patent No. 237,533, dated February 8, 1881.
Application filed August 21, 1880. (No model.) Patented in England November 25, 1879.

To all whom it may concern:

Be it known that I, GEORGE HOWARD, of Berners Street, Oxford Street, in the county of Middlesex, England, have invented certain Improvements in the Construction of Floors and Ceilings, and in the Paneling of Walls and other Surfaces, of which the following is a specification.

The chief object of my invention is to so construct parquet-floors and ordinary floors that their lateral shrinkage may be readily made good, while at the same time provision is made against any injurious effect resulting from the swelling of the wood (however well it may have been seasoned) caused by the dampness to which the flooring of a new building is exposed. Hitherto in laying parquet-floors it has been usual to nail each of the boards composing the panel or slab separately to the joists. This, however, made no provision for shrinkage, and as the boards contracted the joints opened.

According to my invention I provide for the shrinkage and swelling of the parts composing the floor by constructing panels or slabs of boards set side by side and firmly secured together by the means hereinafter mentioned. These slabs I make of any desired size, according to the work in hand, the dimensions of the slabs for ordinary flooring being as large as can be conveniently handled by the workman.

When preparing slabs for parquet-flooring I make them of any required length and of a width sufficient to rest, say, upon three joists, and I fasten one board of each slab (the middle board or one of the end boards) to the joists by means of nails or screws, leaving the other boards composing the slab to rest loosely on the joists. Thus, when the slab shrinks it will shrink laterally or toward the fixed board, away from adjacent slabs in the same line, thereby leaving gaps to be filled in by additional boards. The edges of the lines of slabs thus secured will be held down to the joists by overlapping transverse strips of wood or clamping-pieces having a T or other suitably-shaped cross-section, and forming with the slabs a flush floor-surface.

In Sheet I of the accompanying drawings I have shown my invention as applied to two of

the most ordinary forms of parquet-flooring. Figure 1 is a plan view of a portion of a parquet-floor of the simplest form constructed according to my invention; and Fig. 2 is a cross-section of the same taken on the line 1-2 of Fig. 1.

55 a are a number of boards secured together to form a panel or slab by tongue-and-groove joints, and by the addition of "dog-nails" a', applied to their under surface, as shown in the section, Fig. 3. The boards in this instance 60 are of such length that they will, when in place, rest upon three flooring-joists, b b' b''. Applied to the joists b b' are strips of wood c, T-shaped in cross-section, and serving to form guides for the reception of the slabs, which are rabbeted 65 at their edges to fit against the transverse strips c. The slab is made fast to the joists by nails or screws d, which are passed through the middle board of the slab and take a firm hold of the underlying joists. The strips c are 70 made in lengths somewhat shorter than the slabs, when these are applied to the joists, as shown in the drawings; but when the slabs are secured to the joists in pairs, with their abutting ends made fast to the joists, the strips c 75 may extend to nearly the length of two such slabs.

75 It will be convenient, in laying a floor according to this invention in a newly-built house, to lay the slabs of each row a short distance apart 80 in order to provide for the swelling of the wood transversely of the grain. As the shrinkage occurs gaps are formed, as at e, and these I fill in by the insertion of narrow boards f, which boards I hold in place on the joists by 85 short pieces, c', which will form virtually continuations of the strips c.

85 By securing the short pieces c' to the joists by screws a facile means is provided for removing the filling-pieces f and supplying their 90 place by boards of greater width as the further shrinkage of the panels occurs.

I may remark that the means employed in carrying out my invention admit of various modifications to suit various kinds of wood employed in the formation of the panels and qualities of flooring required to be formed. Thus the panels may be composed of boards

butt-jointed and held together by dog-nails, as shown in Fig. 4, such joints being glued or not, as thought desirable.

In place of forming the strips *c* with a T-shaped section to fit rabbets in ends of the boards composing the slab, the slabs may be held down upon the joist by beveled strips, as shown in the plan and sectional views, Figs. 5 and 6, the edges of the slabs being chamfered to correspond to the bevel of the strips. Fig. 5 shows also the boards of adjacent panels set aslant in opposite directions, as is common in parquet-flooring.

By clamping the slabs to the joists by transverse strips, and securing these strips to the joists in the manner above explained, leaving gaps in the rows of panels, it will be seen that I not only provide for shrinkage and the swelling of the wood, which may be caused by dampness, but I hold down firmly the ends of the boards, and prevent them from curling up and giving the floor an uneven surface.

The application of parquet-flooring is by this invention greatly facilitated, and it may be effected with inconvenience, as respects noise in an inhabited house, when such flooring is required to be applied.

Parquet-flooring constructed after my invention may be laid upon an existing flooring, or with advantage upon a sub-floor, in which cases I should fasten the panels to the existing or sub floor respectively. This will be a convenient arrangement in the event of the joists not being in a suitable position for receiving the attaching nails or screws.

In applying my invention to the construction of ordinary floors I adopt the modification shown in Sheet II of the drawings.

Fig. 7 is a plan view, and Fig. 8 is an end section, of the floor of a small apartment laid down in the simplest manner of which my invention is susceptible. In these figures *a* is a flooring-board placed transversely of the joists, and extending from wall to wall. This board is placed in such a position as to divide up the floor into two equal parts.

bb are two slabs composed of flooring-boards of a length sufficient to reach across the narrow width of the apartment or transversely of the joists, the breadth of the slabs being sufficient to cover the floor-space, but not to touch the walls, of the apartment. These slabs I set in place, making them fast by screwing down or otherwise fixing to the joists the end boards *h* which are brought in juxtaposition with the central board, *a*. The flooring thus constructed will have its edges covered by the skirting *c c*, and it will be free to expand laterally under the skirting, and also to contract without exposing any gap required to be filled. This will be clearly understood by reference to the end section, Fig. 8, which shows a space between the wall and the end of the slab, such space being hidden by the thickness of the skirting. The slabs are composed of boards set side by side and secured by dog-nails, as described with reference to Fig. 3.

For the floors of apartments of larger dimensions it will be necessary to provide fixed guides, which will intervene between the lines of slabs and lie, say, some six feet or more apart, according to the length of planking which it will be convenient to use in making up the slabs. As in large apartments several slabs set end to end will be required to reach from wall to wall in the direction of the shrinkage, the use of filling-pieces must be adopted; and to provide for their insertion short lengths of fixed guides must be introduced to permit, by their temporary removal, of the insertion of the filling-pieces.

In the parquet-flooring above described these fixed guides form part of the floor-surface, and by their use an ornamental character is imparted to the floor.

For ordinary floors—made of pine or other cheap wood—I propose to substitute for these guide-pieces the arrangement shown in plan view at Fig. 9. Fig. 10 is a cross-section of this floor taken on the line 1 2 of Fig. 9, and Fig. 11 is a cross-section on the line 3 4 of the same figure.

dd are strips of iron forming guide-pieces for the slabs. These guides—as will be best seen in the enlarged section and plan views at Fig. 12—lie between the grooves cut in the end edges of the boards composing the slabs *b*, and they are secured to the joists by nails or screws, spacing-collars *d'* being interposed between the strip *d* and the joist *b*. The edges of the slabs are rabbeted below the grooves to provide the requisite clearance, thus allowing of the slabs being slid over the metal strips into place. In this arrangement the flooring is composed of eight slabs, *b*, the flooring-space being divided up into two equal parts by fixed boards *a*. The sides of adjacent slabs will form butt-joints, the metal strips serving to hold them securely in place. These slabs are made fast to the joists by nails or screws passed through the end boards, which abut against the fixed board *a*, and they will thus be free to expand or contract laterally, as above explained.

The invention may also be applied to the covering of walls or parts of walls and ceilings of apartments.

Fig. 13 shows a portion of a wall-covering constructed according to my invention, and Fig. 14 is a section of the same. In these figures *gg* are the panels, constructed as before described, and fitted into rectangular frame-work *hh* in such a manner as to leave them free to expand or contract laterally.

The panel which fills the space between the two stiles and the top and bottom cross-pieces constituting the panel-frame is or may be fixed at the middle of its length to the backing-wall, which is plugged by pieces of wood to receive attaching nails or screws, which are passed through the middle of the panel. This will allow of the panel contracting laterally at its opposite edges. To cover the contraction-spaces, I form the frame-work with deep rab-

bets. Every alternate stile or cross-piece it will be convenient to form of two thicknesses of wood, the facing pieces, which form the overlapping edges, being applied after the 5 panels have been secured in place.

For paneling ceilings, I use substantially the same contrivance as that just described—that is to say, the pieces constituting the panels are secured together by dog-nails or their 10 equivalent. The center of each panel is made fast to the under side of the joists, and the framing for the panels is arranged so as to allow for their free contraction and for the hiding of the spaces caused by their contraction. 15 This mode of covering wall and ceiling surfaces, I would remark, is particularly applicable to the fitting up of floating structures which are exposed to great varieties of climatic influences, ample provision being there- 20 by made for the lateral contraction and expansion of the panels.

Having now explained the nature of my invention, I wish it to be understood that I claim—

A covering for a floor, ceiling, or wall constructed of slabs or panels, each composed of boards joined edge to edge, and having one of its boards made fast to the underlying surface or backing of the floor, ceiling, or wall, transverse guide-pieces for holding the ends 25 30 of said boards in place, and filling-pieces for filling up spaces left between said slabs or panels, substantially as herein described.

Dated the 22d day of July, 1880.

GEO. HOWARD.
